INVENTOR.
Burdsey W. Smith
BY *Samuel M. Lester*
ATTORNEY

UNITED STATES PATENT OFFICE.

BURDSEY W. SMITH, OF OROVILLE, CALIFORNIA.

COMBINED TWINE-HOLDER AND ADVERTISING DEVICE.

1,366,327.

Specification of Letters Patent. Patented Jan. 18, 1921.

Application filed June 15, 1920. Serial No. 389,232.

To all whom it may concern:

Be it known that I, BURDSEY W. SMITH, a citizen of the United States, residing at Oroville, in the county of Butte, State of California, have invented certain new and useful Improvements in Combined Twine-Holders and Advertising Devices; and I do declare the following to be a full, clear, and exact description of the same, reference being had to the accompanying drawings, and to the characters of reference marked thereon, which form a part of this application.

This invention relates to a combined twine holder and advertising device, the principal object of the invention being to provide a device intended for use in retail shops of all kinds, adapted to serve as a holder for twine used to tie around the packages sold, and which, when the twine is pulled from the ball or cone, will cause a certain member to revolve, attracting the purchaser's attention to advertising matter or display labels carried by said member.

A second object is to provide a neat and attractive device, concealing the twine, and adapted to be mounted either to the wall or on a counter of the store, occupying a minimum of space.

A further object of the invention is to produce a simple and inexpensive device, and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a perspective elevation of my device.

Fig. 2 is a fragmentary cross section of the base portion.

Referring now more particularly to the characters of reference on the drawings, the numeral 1 denotes a supporting bracket comprising a vertical member 2 and horizontal arms 3 and 4 at the upper and lower ends respectively.

Projecting upwardly from the outer end of the arm 4 is a boss 5 having a screw 6 secured therein, adjacent the upper end of which is fixed a forked member 7 adapted to project into the core of a twine-cone 8 to hold the latter vertically and against rotation.

Surrounding the cone and turnably mounted on the screw 6 below the fork 7 is a cylinder 9, preferably of a size and shape equal or similar to those in which certain standard goods, such as canned food products, are packed. The upper end of this cylinder is open, and is about on a level with the top of the twine.

The member 9 is somewhat flexibly mounted on the screw or pin 6, in order to permit it to be tipped to one side out of the way of the overhanging arm 3 for the insertion of the twine-cone, and to maintain it normally in vertical alinement, I provide a vertical arm 10 pivoted to the cylinder adjacent the top thereof, and having an upper horizontal extension 11 adapted to removably and turnably slip onto a tube 12 depending from the arm 3. The member 10—11 is preferably flexible, so that it may be sprung down out of engagement with the tube, and then swung down to one side, so that the cylinder may be tipped as stated. Horizontal arms 13 and 14 are pivoted to the ends of the arms 3 and 4 respectively and project beyond the plane of the sides of the cylinder.

The twine from the cone is threaded through the tube 12, then through an eye 15 fixed to the arm 13, then through an orifice 16 provided in the latter near the outer end thereof. From this point it is carried downwardly and through an orifice 17 provided in a vertical plate 18 fixed to the outer end of the arm 14, and then around a sheave 19 fixed to the bottom of the cylinder 9 and through an orifice 20 in the opposite end of the plate 18.

When the twine is pulled from its free end beyond the orifice 20, it will grip the sheave, and rotate the cylinder connected thereto. This cylinder is adapted to carry a label 21 which is preferably a facsimile of that carried on the cans of the product being featured or advertised.

A grooved holder 22 may be provided on the cylinder, to receive a price tag 23.

Also a clip member 24 may be pivotally mounted on the arm 3 to receive a card 25 which may also bear descriptive matter or price information about the article featured by the cylinder.

The label 21 may of course be torn off and a different one posted on whenever it is desirable, while the tag 23 and card 25 may be removed at will.

The device may be firmly attached to a wall by means of the vertical bracket member 2, or to a counter by the horizontal arm 4.

5 By means of the pivoted arms 13 and 14, the latter may be turned about the bracket so that the twine may be led to one side or the other of the cylinder, as may be convenient.

10 From the foregoing description it will be readily seen that I have produced such a device as substantially fulfils the object of the invention as set forth herein.

While this specification sets forth in detail the present and preferred construction of the device still in practice such deviations from such detail may be resorted to as do not form a departure from the spirit of the invention, as defined by the appended 20 claims.

Having thus described my invention what I claim as new and useful and desire to secure by Letters Patent is:—

1. A device of the character described 25 comprising a turnably mounted cylinder, a

display label thereon, having a cone of twine mounted therein and held against turning, and means for so leading the twine from the cone that when pulled at its free end the cylinder will rotate.

2. A device of the character described comprising a cylinder shaped to represent a standard package of goods, a display label thereon which is a facsimile of that carried by such package, a cone of twine concealed in the cylinder and held against turning, and means whereby the cylinder will be rotated when the twine is pulled from the cone.

3. A device of the character described, comprising a fixed bracket, a cylinder turnably mounted thereon and adapted to receive a cone of twine, and a sheave fixed to the cylinder and concentric therewith, the twine from the cone being passed around the 40 sheave and terminating therebeyond, whereby when the twine is pulled at such termination, the cylinder will revolve.

In testimony whereof I affix my signature.
BURDSEY W. SMITH.
